UNITED STATES PATENT OFFICE

JULIUS J. BLUMENTHAL, OF NEW YORK, N. Y., ASSIGNOR TO LIGHTING APPLIANCE COMPANY, INC., OF NEW YORK, N. Y.

DESIGN FOR A LIGHTING FIXTURE OR ARTICLE OF SIMILAR NATURE

Application filed August 8, 1930. Serial No. 36,603. Term of patent 3½ years.

To all whom it may concern:

Be it known that I, JULIUS J. BLUMENTHAL, a citizen of the United States, residing in New York, in the county of Kings and State of New York, have invented a new, original, and ornamental Design for a Lighting Fixture or Article of Similar Nature, of which the following is a specification, reference being had to the accompanying drawings, forming a part thereof.

Figure 1 is a perspective view of a light-

ing fixture showing my new design. Fig. 2 is a diagrammatic plan view for the purpose of illustrating contour.

The view from the sides and rear is similar to that shown in the drawings.

I claim:

The ornamental design for a lighting fixture or article of similar nature, as shown and described.

In testimony whereof I affix my signature.

JULIUS J. BLUMENTHAL.
